COMBINED LANE DELINEATOR-DIRECTION INDICATOR DEVICE FOR ROADWAYS

Rolf W. Peter, Palo Alto, Calif., assignor to Tucker
Associates, Inc., Palo Alto, Calif., a corporation of
California

Filed Oct. 7, 1968, Ser. No. 13,852

Term of patent 14 years

Int. Cl. D29—99

U.S. Cl. D72—1

FIG. 1.

FIG. 2.

FIG. 3.

FIG. 4.

FIG. 5.

FIG. 6.

FIG. 7.

FIG. 8.

FIG. 1 is a top plan view of the combined lane delineator-direction indicator device for roadways embodying my new design.

FIG. 2 is a rear end view thereof.

FIG. 3 is a side elevational view thereof.

FIG. 4 is a front end view thereof.

FIG. 5 is a top plan view of a second embodiment of my new design.

FIG. 6 is a rear end view thereof.

FIG. 7 is a side elevational view thereof.

FIG. 8 is a front end view thereof.

The roadway and additional lane delineator-direction indicator devices are shown in broken lines in FIGS. 1-8 for illustrative purposes only and form no part of the claimed design.

I claim:

The ornamental design for combined lane delineator-direction indicator device for roadways, substantially as shown and described.
